DESIGN FOR AN INFANT'S CLOAK.

2065

2065

UNITED STATES PATENT OFFICE.

ETTA L. JENKINS, OF NEW YORK, N. Y., ASSIGNOR TO THE BUTTERICK PUBLISHING COMPANY, (LIMITED,) OF SAME PLACE.

DESIGN FOR AN INFANT'S CLOAK.

SPECIFICATION forming part of Design No. 18,288, dated May 1, 1888.

Application filed April 2, 1888. Serial No. 209,325. Term of patent 3½ years.

To all whom it may concern:

Be it known that I, ETTA L. JENKINS, of the city, county, and State of New York, have invented and produced a new and original Design for a Pattern of an Infant's Cloak; and I do hereby declare that the engraved prints accompanying this specification convey to any one accustomed to using paper patterns a clear understanding of how a garment made up by the pattern will appear.

The design shows full fronts that display a cluster of smocking above the lower edge at either side of the closing, a back exhibiting

box-plaits from the neck down, a full skirt depending from the lower edges of the fronts and back, a deep cape-collar, and coat-sleeves.

What I claim as my invention, and desire to secure by Letters Patent, is—

The design for an infant's cloak, as shown in the engraved prints accompanying this specification.

ETTA L. JENKINS.
